United States Patent Office.

F. S. PEASE, OF BUFFALO, NEW YORK.

Letters Patent No. 65,594, dated June 11, 1867.

IMPROVED BLAST APPARATUS FOR CARBURETTERS.

The Schedule referred to in these Letters Patent and making part of the same.

TO ALL WHOM IT MAY CONCERN:

Be it known that I, F. S. PEASE, of Buffalo, in the county of Erie, and the State of New York, have invented a new and useful Improved Blast Apparatus for Carburetters; and I do hereby declare the following to be a full, clear, and exact description of the same, sufficient to enable one skilled in the art to which it appertains to construct and use the same, reference being had to the accompanying drawing, making part of this specification, and in which drawings—

Figure 1 is a perspective view; and

Figures 2 and 3 are detached views.

The object of the improvement is a cheap and effective apparatus for producing a continuous blast for carburetters, and the means employed consists of a series of bellows below an upper one which collects the air from the others, the lower bellows being operated by cams on a revolving shaft by a weight or spring. The cams are preferred for this purpose, as they are readily attached to a straight shaft and disposed thereon in such circular relation as to act consecutively upon the lower bellows, so that the blast of air is constantly passing into the upper reservoir whose weight gives it an equable discharging force.

I have aimed at in this arrangement to secure economy and simplicity with effectiveness, and prefer the cams in the former respect for the reason of the cheapness of fitting, and from the fact that the lower board of the bellows is allowed to drop freely as soon as the cam passes it to the extent allowed it by the cords which attach the lower boards of the respective bellows to the bed board of the upper one. By this means the blast capacity is regulated, as the shortening of the string will cause the bellows to hold less, and a revolution of the shaft will discharge a smaller volume of air. The bellows are strongly constructed, with wooden plates attached to each other and to the upper and lower boards by elastic strips, so that a blast of considerable power may be attained without bagging outwardly the membrane which connects the upper and lower portions of the bellows. The valves in the upper and lower reservoir bellows open upward, and the blast is educted through the pipe *a* and carried to the carburetter. A weight attached to the strap *b*, which is wound on a pulley on the cam-shaft, constitutes the motive power of the machine. A spring may be substituted therefor, if preferred.

If preferred, each cam may have three or four prongs, so as to act upon the bellows a corresponding number of times at every revolution of the shaft. (See fig. 3.)

Having described my invention, what I claim as new, and desire to secure by Letters Patent, is—

The arrangement of the shaft *A*, cams *B* *B*, dividing the circle and operating the bellows of corresponding number, which are adjusted as to capacity by the check-strings *c*, the whole constructed and operated substantially as described and represented.

To the above specification of my improvement I have signed my hand this 19th day of March, 1867.

F. S. PEASE.
